(57) **CLAIM**

The ornamental design for a spacer bracket, as shown and described.

DESCRIPTION

FIG. 1 is an isometric view of the top of the spacer bracket, showing my new design;

FIG. 2 is an isometric view of the bottom of the spacer bracket thereof;

FIG. 3 is a top plan view of the spacer bracket thereof;

FIG. 4 is a bottom plan view of the spacer bracket thereof;

FIG. 5 is a front elevational view of the spacer bracket thereof, the back elevational view being a mirror image; and,

FIG. 6 is a left side elevational view of the spacer bracket thereof, the right side elevational view being a mirror image. The broken lines in the drawings illustrate portions of the spacer bracket which form no part of the claimed design.
